(57) **CLAIM**

The ornamental design for a network device, as shown and described.

DESCRIPTION

FIG. 1 is a perspective view of a network device showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is another perspective view thereof.

The broken lines in each of FIGS. 1–8 show portions of the network device that form no part of the claimed design.

The surface shading and contour lines shown in FIGS. 1–8 represent the three-dimensional character and contour of the network device, and are not intended to limit the network device to any particular material, color, or surface decoration.
